GRINDING MACHINERY

Lester F. Nenninger, Cincinnati, Ohio, assignor
to Cincinnati Grinders Incorporated, Cincinnati, Ohio, a corporation of Ohio

Application May 3, 1933, Serial No. 669,212

9 Claims. (Cl. 51—49)

This invention relates to improvements in grinding machines and especially to improvements in such machines which have an oscillably mounted grinding wheel head.

5 An object of the invention is the provision of improved means for effecting and controlling the oscillation of the said head.

Another object of the invention is the provision of improved compensating and adjusting 10 mechanism utilizable with oscillating head type of grinding machines whereby the said head may be more correctly and readily controlled.

15 A further object of the invention is the provision of a machine as above specified, having particular application for grinding large rolls and in which the said controlling and adjusting mechanism are conveniently disposed with respect to the operator's position or station.

20 A still further object of this invention is the provision of improved means for effecting an accurate and sensitive adjustment of the grinding wheel and work relative to one another, for example about the axis of oscillation of the head, whereby minute adjustment may be made to 25 compensate, for example, for wheel wear, as well as for effecting extremely light cleanup or finishing cuts.

25 Other objects and advantages of the present invention should be readily apparent by reference to the following specification considered in conjunction with the accompanying drawings forming a part thereof, and it is to be understood that any modifications may be made in the exact structural details there shown and described within the scope of the appended claims 30 without departing from or exceeding the spirit of the invention.

In the drawings:

35 Figure 1 is a front elevation of a grinding machine embodying the improvements of this invention.

40 Figure 2 is a top plan view of the machine illustrated in Figure 1.

45 Figure 3 is a transverse sectional view through the machine as seen from line 3—3 on Figure 1.

Figure 4 is an elevational view of the grinding wheel traversing mechanism, as seen for example from line 4—4 on Figure 2.

50 Figure 5 is a vertical sectional view through the grinding wheel traversing mechanism taken in a plane behind the plane of Figure 4.

Figure 6 is a fragmentary view, partly in elevation and partly in section, as seen, for example, from line 6—6 on Figure 5.

55 Figure 7 is a fragmentary sectional and eleva-

tional view illustrating the mechanism for effecting the oscillation of the grinding wheel head as seen, for example, on line 7—7 on Figure 3.

Figure 8 is a sectional view taken on line 8—8 of Figure 3.

Throughout the several views of the drawings similar reference characters are employed to indicate the same or similar parts.

As was above noted this invention pertains to improved mechanism for adjusting and effecting the position and oscillation of an oscillatory type of grinding wheel head. The mechanism is illustrated in the drawings as being utilized with roll grinders for the larger types of rolls, but it is to be understood that it has equal application to other types of grinding machines or machine tools generally, whether employed for finishing mill rolls or not. In general the machine comprises a bed supporting the work carrying members and the grinding wheel carriage, one of which is adapted to be axially shifted to effect a relative traverse between the work and grinding wheel. In addition the machine comprises means for effecting the oscillation of the grinding wheel or the work toward and from the other during the said traversing thereof, together with means for effecting the rotation of the work and the grinding. This invention has particular reference to the mechanism included in the mechanism for effecting the oscillation of the wheel and particularly to means for adjusting this means.

The machine specifically illustrated in the drawings comprises a bed 15 mounted on a concrete foundation 16, here shown as what might be termed an island. The foundation 16 is entirely surrounded by a channel 17, containing the coolant to be supplied to the work and wheel during the grinding operation as is usual in grinding practice. The channel 17 terminates on one side at the level of the floor and on the other side at the level of the foundation which is disposed below the floor level.

The machine bed 15 is provided on one end with a supporting surface 18 on which is disposed the work driver or headstock 19. The headstock 19 has projecting therefrom the center 20, which is surrounded by a face plate 21, carrying the driving dogs 22. Any suitable or desirable means may be employed for rotating the face plate 21 and dogs 22, but as here shown this mechanism 23 comprises an electric motor or prime mover 23 coupled through the coupling 24 with a driving shaft 25 associated with the headstock 19.

The bed 15 from the supporting surface 18 to its other end is provided with guideways 26 and 27,

5

20

25

35

40

45

50

55

the former being a flat way, while the latter is of the inverted V type. Mounted on the guide ways 26 and 27 for movement there along is a tailstock 28, from which projects the center 29 in axial alignment with the headstock center 20, and together roughly positioning the work on the bed. The work 30 is shown in Figures 1 and 2 in phantom lines, from opposite ends of which project journal bearings 31 and 32. These bearings are 10 respectively supported by journal rests 33 and 34, which determine the axis about which the roll is to be rotated as is the usual practice with machines of this type.

The bed 15 is provided with a rearward extension 15 on which is formed throughout its length a pair of flat and V guideways 36 and 37. Mounted on the guideways 36 and 37 for movement there along is a bed plate 38, which supports a slide 39 for the grinding wheel carriage 40. The bed plate 20 38 in addition supports the mechanism for effecting the translation thereof, as well as providing the operator's station. For this latter purpose the bed plate has extending upwardly therefrom a pedestal 41 for the operator's seat 42. Within 25 reach of the operator's seat 42 is the mechanism, as will later be described, for controlling all of the movements of the several units of the machine.

The mechanism for traversing the bed plate 38 and parts carried thereby is best illustrated in 30 Figures 4, 5, and 6, and as there shown, comprises a housing 43 to which is exteriorly secured a shelf 44 supporting an electric motor or prime mover 45. The shaft 46 of the motor 45 projects interiorly of the housing 43 and is rotatively journaled 35 in bearings provided thereby. Loosely mounted on the shaft 46 is a spur gear 47 and bevel gear 48. Splined to the shaft between these gears is a clutch member 49, having provided on one face clutch teeth 50 for engagement with complementary 40 clutch teeth 51 on the adjacent face of the spur gear 47. The clutch member 49 is provided on its other side with clutch teeth 52 adapted to engage with complementary clutch teeth 53 on the adjacent face of the bevel gear 48. From this it will 45 be seen that depending upon the position of the clutch member 49, either the spur or bevel gear will be connected with the shaft. In order to effect the adjustment or shifting of the clutch member it is provided with a circumferential 50 groove 54, receiving the forked end of a shifter lever 55 keyed or otherwise secured to a shaft 56 that projects beyond one face of the housing 43. Secured to the said projecting end of the shaft 56 is a manually actuable lever 57 whereby movement 55 thereof effects oscillation of the shaft 56 and shifter fork 55.

In axial alignment with the shaft 46 and rotatively supported by the other wall of the housing 43 is a shaft 58, having loosely mounted 60 thereon a spur and bevel gear 59 and 60. These gears may be independent gears keyed to one another for simultaneous rotation or may be integral as illustrated in Figure 5. The spur gear 59, see Figure 6, meshes with a gear 61 keyed or 65 otherwise secured to a shaft 62, rotatively journaled in the walls of housing 43. This shaft 62 has keyed to its other end a second gear 63 which meshes with the spur gear 47, loosely journaled on the motor shaft 46. From this it will be seen 70 that depending upon the position of the clutch member 49 either the bevel gear 48 will be driven direct or the bevel gear 60 will be rotated through the transmission line, including the gears 47, 63, 61 and 59.

This mechanism constitutes a reversing mech-

anism since the gear 48 will be driven in the opposite direction from that of the gear 60. The bevel gears 48 and 60 are at all times in mesh with a large bevel gear 64, loosely journaled on a driving shaft 65. In order to be clutched or keyed to this shaft the bevel gear 64 is provided with clutch teeth 66 adapted to be engaged by clutch teeth 67 on one side of clutch member 68. The clutch member 68 is provided with a circumferential groove 69, receiving the 10 forked end 70 of a clutch shifter lever 71, keyed or otherwise secured to a shaft 72 journaled in the housing 43 and projecting beyond the face thereof. The projecting end of the shaft 72 carries a manually actuable lever 73 whereby the 15 clutch is shifted into and out of engagement with the bevel gear 64.

The above described mechanism constitutes a power reversing drive for the drive shaft 65 and in order to effect the manual rotation of the 20 shaft, such as for set-up purposes and the like, the following mechanism is resorted to. The clutch member 68 is provided on its other side with clutch teeth 74 adapted to engage with clutch teeth 75 formed on the adjacent face of 25 a worm wheel 76 loosely journaled on the shaft 65. Meshing with the worm wheel 76 is a worm 77 integral with or secured to a worm shaft 78, journaled in the walls of the housing 43 and projecting beyond the forward face thereof. 30 Keyed or otherwise secured to this extending portion of the worm shaft 78 is a hand wheel 79 whereby the said shaft and consequently the worm are manually rotated. From this will be seen that the shaft 65 may be manually actuated 35 in reverse directions.

In axial alignment with the drive shaft 65 and journaled in the bed plate 38 is a driven shaft 80, carrying on its lower end a rack pinion or gear 81 meshing with the teeth of rack bar 82 40 secured to the bed extension 35 and shown in Figure 5 as secured to the inner longitudinal edge of the V guide way 37 formed thereon. It is the shaft 80 that is power driven through the above described power drive reversing mechanism and the manual drive operable on the driving shaft 65. This shaft therefore is adapted to be connected with the drive shaft 65 for effecting the rotation of the shaft 80. As illustrated in the drawings the shafts 65 and 80 may be directly coupled for driving the driven shaft at a high speed or indirectly coupled for driving the said shaft at a low speed.

This mechanism comprises a clutch member 83 splined on the shaft 80 and being provided on 55 opposite sides thereof with clutch teeth 84 and 85. The clutch 83 is provided with a circumferential groove 86 receiving the forked end 87 of clutch shifter lever 88, keyed or otherwise secured to a shaft 89 journaled in and projecting 60 beyond the housing 43. To the projecting end of the shaft 89 is secured a lever 90 whereby the said shaft is oscillated for correspondingly oscillating the clutch lever 88 and shifting the clutch member 83.

For effecting a direct coupling between the driving shaft 65 and the driven shaft 80 the clutch teeth 84 are adapted to engage complementary clutch teeth 91 formed on a gear 92 keyed or otherwise secured to the lower end of 70 the driving shaft 65. In order to indirectly couple the said shafts the clutch teeth 85 are adapted to engage with complementary clutch teeth 93 formed on a large gear 94 keyed near the upper end of the driven shaft 80. Meshing 75

with the gear 94 is a pinion 95 keyed to the lower end of an intermediate shaft 96 rotatively journaled in a boss or lug 97 projecting inwardly from one wall of the housing 43. The shaft 96 extends entirely through the said boss or lug 97 and has keyed to its upper end a second gear 98 which meshes with the gear on the driving shaft 65. From this it will be seen that the shaft 80 is rotated at one speed, by being directly coupled with the driving shaft 65, and at a different speed through the gear train, including the gears 98, 95 and 94, and that the bed plate 38 and parts carried thereby are correspondingly traversed relative to the guiding ways on the bed extension 35.

As was above noted, the bed plate 38 has mounted thereon a slide 39 which supports the grinding wheel carriage 40. The slide 39 is adapted to be actuated relative to the bed plate 38 toward and from the work for which purpose it is provided with a lug 99 in which is secured a nut 100, having threads adapted to mesh with the threads of a cross feed screw 101. The screw 101 is mounted for rotation but not axial adjustment in a bracket 102 secured to the rear end of the bed plate 38. In order to rotate the screw 101 it has keyed or otherwise secured to it a worm wheel 103 having meshed therewith a worm 104 on the end of a worm shaft 105. The worm shaft 105 is connected in any desirable manner with the motor shaft of an electric motor or prime mover 106, see Figure 2, mounted on the bed plate 38 to one side of the slide. From this it will be seen that the grinding wheel carriage, together with the slide and parts carried thereby, may be adjusted toward and from the work.

The slide 39 is provided at its forward end with a trunnion bearing 107 in which is rotatively mounted a trunnion shaft 108 which is carried by depending lugs 109 carried by the grinding wheel carriage 40 and whereby the said carriage is oscillatably mounted for movement toward and from the work. The carriage 40 provides suitable bearings 110 in which is journaled a spindle 111 having secured to its one end a grinding wheel 112. The grinding wheel 112 is partially enclosed by a hood or guard 113 for confining the coolant usual with grinding machines. Mounted on the upper surface of the carriage 40 is an electric motor or prime mover 114 connected by a suitable transmission enclosed within the guard 115, see Figure 2, with the grinding wheel spindle 111 whereby the said spindle and grinding wheel are rotated at the usual high or grinding rate of speed.

In order to effect the oscillation of the slide 39, carriage 40 and grinding wheel 112 toward and from the work the bed extension 35 has secured to its rear surface a cambering mechanism comprising a supplementary bed or support 116. The supplementary bed or support 116 is formed in its upper surface with a guide way 117 in which is mounted for movement relative thereto a carriage 118, supporting a cambering bar 119. The carriage 118 is provided on its under surface with a rack bar 119' having its teeth meshing with a rack pinion 120 integral with or secured to a shaft 121. The projecting end of the shaft 121 is formed to receive a wrench whereby the carriage and parts carried thereby may be adjusted with respect to the support 116 to dispose the cambering bar in the same relation with respect to the supporting bed as the work bears thereto. The

cambering bar 119 is mounted in a way 122 formed longitudinally in the upper surface of the carriage 118 and is supported in said way by pins 123 and 124. Formed along one surface of the cambering bar 119 is a lug 125 adapted to be engaged on its upper surface by pins 126 and 127. The cambering bar 119 is relatively flexible whereby it may be bent or deformed in accordance with the desired contour to be formed on the work. This bending or deformation of the bar 119 takes place in a downward direction about the pins 123 and 124, and in an upward direction about the pins 126 and 127. Any suitable means may be employed for effecting this bending of the bar, use in the present instance being made of bending screws 128 disposed in the carriage intermediate the bending pins. After the bar has been adjusted to the desired form clamp screws 129 are employed to lock same in position.

By reference to Figures 1 and 2 it will be noted that the ends of the rolls are provided with bevels 130 which are formed by means of adjustable cam members 131 and 132 secured to the carriage 118 for movement therewith. These cam members 131 and 132 are adjustable relative to the cambering bar 119 and may be positioned at any desired point with respect thereto, depending upon the desired contour to be provided on the work.

Riding on the upper surface 133 of the bar 119 is a roller 134 rotatively carried by an arm 135 keyed or otherwise secured to the outer end of a spline shaft 136 rotatively journaled in a bearing 137 secured to the rear end of the bed plate 38. The spline shaft 136 is disposed in bushings 138 journaled for oscillation in lugs 139, depending from the underside of the slide 39, and has splined thereto, between the lugs 139, to partake of the oscillatory movement of the shaft, a finger or arm 140. The outer end of the arm 140 contacts with the lower end of a screw or plunger 141 associated with the carriage 40. The screw or plunger member 141 constitutes the coupling between the carriage 40 and the mechanism operable by the cambering bar 119 whereby the carriage 40 is oscillated in accordance with the contour of the bar 119.

In order to take up for inevitable wear on the grinding wheel 112 and to compensate for the removal of material from the wheel, as by trueing, the carriage 40 is adapted to be independently adjusted about the trunnion 108. For this purpose the screw 141 is threaded into a nut 142 rotatively journaled in a lug 143, forming a part of the carriage 40 and supported, for example, by a web 144 integral with the carriage. The nut 142 has secured to it or formed integral therewith a worm wheel 145 in mesh with a worm 146 on a worm shaft 147. The worm shaft 148 projects beyond the wall of the carriage 40 to receive a hand wheel 149 whereby the said worm is rotated.

From the foregoing it will be noted that the carriage 40 and grinding wheel 112 carried thereby are actuated about the axis of the trunnion 108 to feed grinding wheel 112 into the work in accordance with the contour provided on the cam bar 119. It will further be noted that since the cam bar is shaped throughout its length the work or roll being operated upon will be correspondingly shaped from end to end.

By reference to Figure 2 it will be noted that the housing 43 containing the bed plate traversing mechanism has the operating levers 57, 73 75

and 89 projecting therefrom on the side adjacent the operator's station or seat 42. It will also be noted that the hand wheel 79 projecting from this housing is also disposed on the operator's 5 side of the housing so that the said levers and hand wheel are within reach without requiring the operator to leave his station. It will further be noted that the hand wheel 148 for the grinding wheel slide adjusting and compensating mechanism projects from the side of carriage 40 which is also adjacent the operator's station whereby he can readily control the movement thereof.

The several motors, such as the work driving motor 23, the wheel rotating motor 114, the grinding wheel traversing motor 45 and the slide adjusting motor 106 are disposed at points remote from the operator's station which might cause him to leave his position to effect their 10 operation. In order to avoid this, however, the switch panel or control mechanism is mounted on the bed plate 38 within convenient reach of the operator. For this purpose the bed plate has rising therefrom a bracket or standard 149 having secured to it on the side adjacent the operator's seat 42 a switchboard or panel 150 carrying a plurality of control switches 151. From this it will be seen that any one of the several motors may be controlled from the operator's station, the same as the adjustment and control of the traversing mechanism for the grinding wheel mechanism.

It is believed that the operation of this machine will be readily understood and that means are provided for manually oscillating the grinding wheel toward and from the work, means are provided to compensate for wear and removal of material from the grinding wheel to insure proper engagement between the wheel and the work and that the machine is at all times under the immediate control of the operator while he is in the most advantageous position for observing the action of the wheel on the work.

What is claimed is:

45 1. In a grinding machine of the class described the combination of a bed, a grinding wheel support mounted thereon for a translation relative thereto, a slide on the support for transverse adjustment relative thereto, a grinding wheel carriage pivotally mounted on the slide for oscillation in the direction of adjustment of the slide, power means for actuating the slide, manual means for oscillatably adjusting the carriage, additional power means for oscillating the carriage, a coupling between the power oscillating means and carriage whereby the power oscillating means is effective regardless of the adjustment of the slide with respect to the support, including a spline shaft adapted to be oscillated by the power oscillating means, an arm in operative engagement with the spline shaft and shiftable relative thereto with the slide, and an axially adjustable plunger contacting with the arm and forming a part of the manual oscillating means.

2. In a grinding machine of the class described the combination of a bed, a grinding wheel support mounted thereon for a translation relative thereto, a slide on the support for transverse adjustment relative thereto, a grinding wheel carriage pivotally mounted on the slide for oscillation in the direction of adjustment of the slide, power means for actuating the slide, manual means for oscillatably adjusting the carriage, additional power means for oscillating the

5 means and carriage whereby the power oscillating means is effective regardless of the adjustment of the slide with respect to the support, including a spline shaft adapted to be oscillated by the power oscillating means, an arm in operative engagement with the spline shaft and shiftable relative thereto with the slide, an axially adjustable plunger contacting with the arm and forming a part of the manual oscillating means, and means adjusting the position of the power carriage oscillating means with respect to wheel support.

3. In a grinding machine the combination of a bed, means on the bed for supporting a work piece for rotation about a predetermined axis, a grinding wheel assembly supported by said bed and including a slide adapted to be translated on the bed axially of the work, a second slide on the first slide for movement transversely thereof toward and from the work axis, a grinding wheel carriage pivotally connected to the second slide to partake of the transverse movements thereof, a mechanism including inter-engaged nut and screw elements for effecting an oscillation of the carriage about its pivotal connection wherein one of the said elements is rotatably supported by the carriage while the other is held against rotative movement but has a sliding connection therewith, and manually operable means connected with said rotatable element and terminating in a hand wheel for effecting the rotation thereof.

4. In a grinding machine the combination of a bed, means on the bed for supporting a work piece for rotation about a predetermined axis, a grinding wheel assembly supported by said bed and including a slide adapted to be translated on the bed axially of the work, a second slide on the first slide for movement transversely thereof toward and from the work axis, a grinding wheel carriage pivotally connected to the second slide to partake of the transverse movements thereof, a mechanism including inter-engaged nut and screw elements for effecting an oscillation of the carriage about its pivotal connection wherein one of the said elements is rotatably supported by the carriage while the other is held against rotative movement but has a sliding connection therewith, and manually operable means connected with said rotatable element and terminating in a hand wheel for effecting the rotation thereof, and additional means for effecting an oscillation of the carriage independent of the oscillation imparted thereto by the screw and nut mechanism and effective during the translation of the grinding wheel unit.

5. In a grinding machine the combination of a bed, means on the bed for supporting a work piece for rotation about a predetermined axis, a grinding wheel assembly supported by said bed and including a slide adapted to be translated on the bed axially of the work, a second slide on the first slide for movement transversely thereof toward and from the work axis, a grinding wheel carriage pivotally connected to the second slide to partake of the transverse movements thereof, a mechanism including inter-engaged nut and screw elements for effecting an oscillation of the carriage about its pivotal connection wherein one of the said elements is rotatably supported by the carriage while the other is held against rotative movement but has a sliding connection therewith, and manually operable means connected with said rotatable element and terminating in a hand wheel for effecting the rotation thereof, and a

- cambering mechanism operable during the translation of the grinding wheel unit operable through the screw and nut mechanism for effecting the oscillation of the carriage independent of said oscillation as imparted thereto by the manual means.
6. In a grinding machine the combination of a bed, means on the bed for supporting a work piece for rotation about a predetermined axis, a grinding wheel assembly supported by said bed and including a slide adapted to be translated on the bed axially of the work, a second slide on the first slide for movement transversely thereof toward and from the work axis, a grinding wheel carriage pivotally connected to the second slide to partake of the transverse movements thereof, a mechanism including inter-engaged nut and screw elements for effecting an oscillation of the carriage about its pivotal connection wherein one of the said elements is rotatably supported by the carriage while the other is held against rotative movement but has a sliding connection therewith, manually operable means connected with said rotatable element and terminating in a hand wheel for effecting the rotation thereof, a cambering mechanism operable during the translation of the grinding wheel unit operable through the screw and nut mechanism for effecting the oscillation of the carriage independent of said oscillation as imparted thereto by the manual means, including an oscillatable shaft having an angular cross section adapted to be oscillated by the cambering mechanism, and a member slidably mounted on said shaft to partake of the oscillations thereof and forming a thrust member for the rotatable part of the screw and nut mechanism.
7. In a grinding machine the combination of a bed, means on the bed for supporting a work piece for rotation about a predetermined axis, a grinding wheel assembly supported by said bed and including a slide adapted to be translated on the bed axially of the work, a second slide on the first slide for movement transversely thereof toward and from the work axis, a grinding wheel carriage pivotally connected to the second slide to partake of the transverse movements thereof, a mechanism including inter-engaged nut and screw elements for effecting an oscillation of the carriage about its pivotal connection wherein one of the said elements is rotatably supported by the carriage while the other is held against rotative movement but has a sliding connection therewith, manually operable means connected with said rotatable element and terminating in a hand wheel for effecting the rotation thereof, a cambering mechanism operable during the translation of the grinding wheel unit operable through the screw and nut mechanism for effecting the oscillation of the carriage independent of said oscillation as imparted thereto by the manual means, including an oscillatable shaft having an angular cross section adapted to be oscillated by the cambering mechanism, a member slidably mounted on said shaft to partake of the oscillations thereof and forming a thrust member for the rotatable part of the screw and nut mechanism, and means connecting the shaft member with the transversely shiftable slide whereby the cambering mechanism effects the oscillation of the carriage regardless of the transverse position of the second slide.
8. A grinding machine of the character described, including a bed, a slide supported by the bed for transverse movement with respect thereto, a grinding wheel carriage pivotally connected to the forward portion of said slide and supporting a grinding wheel adjacent the point of pivotance thereof, and a driving motor for the grinding wheel at a point remote from said pivot, a 10 plunger member adjustably supported by the grinding wheel carriage at a point adjacent the motor and depending through the slide, a cambering device carried by the bed and terminating in a spline shaft extending parallel with the direction of movement of the slide, spaced means on the slide providing bearings for said shaft, an abutment member mounted on the shaft between said spaced means whereby said member is translated with the slide relative to the spline shaft, 20 said member having a portion for engagement with the plunger of the grinding wheel carriage whereby the cambering mechanism will correspondingly react through the plunger against the carriage in any transversely adjusted position of 25 the slide, and operating mechanism inter-engaged with the plunger for effecting a longitudinal adjustment thereof with respect to its supporting carriage, whereby the effective zone of movement of the grinding wheel under influence of the cambering mechanism may be shifted as desired.
9. A machine for the grinding of large rolls or the like including a bed unit, roll supporting means carried thereby, a main slide supported for longitudinal movement relative to the bed, a supplemental slide carried by the main slide and movable transversely of the bed in a direction toward and from the work supporting means, a grinding wheel carriage pivotally secured to the inner portion of the second slide, a grinding wheel 35 rotatably supported by the carriage, and means for determining the effective relation between the grinding wheel and a work piece when in position in the machine, said means including a cambering bar carried by the bed, a transversely extending 40 spline shaft journaled in the longitudinally movable slide, means interconnecting the shaft and bar for effecting an oscillation of the shaft, the transverse slide having spaced bearings slidably 45 engaging the shaft, an actuating abutment splined on the shaft and disposed between said spaced bearings whereby said abutment may oscillate with the shaft but will be translated relative thereto on transverse movement of the second slide, a plunger member slidably but non-rotatably 50 inter-engaged with the grinding wheel carriage, said plunger having a terminal portion engaging the abutment and having an intermediate threaded portion, a nut member rotatably but non-translatable secured to the carriage and circumscribing the threaded portion of the plunger, and means for effecting a rotation of said nut about the threaded portion of the plunger whereby a longitudinal movement of the plunger with respect to the carriage will be effected definitely 55 to vary the angular relationship of the carriage and slide supplementing the variants effected by reaction of the cambering bar on the plunger engaging abutment.

LESTER F. NENNIGER.
